ABSTRACT OF THE DISCLOSURE

An apparatus for wrapping components having flat metal cores, such as electrical resistors, with a blank of insulating material. An indexing turret having component holding fixtures is surrounded by work stations, one of which is provided with a component feeding device, which, after each index of the turret, automatically loads a component into one of the fixtures with the core projecting radially outward from the turret. At another of the work stations, a wrapping device is provided to receive the core of each component on each indexing, and the wrapping device is simultaneously fed with a heated blank which is then folded about the core before the next indexing of the turret.

This invention relates to a component wrapping apparatus, and more particularly, to a machine for wrapping the flat metal cores of electrical components, such as certain types of resistors, with a blank insulating material such as sheet phenolized asbestos.

Known operations of production of electrical components having flat metal cores with terminals extending from one end, such as certain types of resistors, have been relatively slow and involved considerable manual labour. Due to the fact the sheet phenolized asbestos is very brittle when at normal room temperatures, it must be heated prior to folding it around the flat plate portion of the core to avoid fracturing of the phenolized asbestos along the fold lines of the blanks. However, because the phenolized asbestos blanks with the sealing adhesive thereon become very sticky when heated, in one known type of wrapping machine, which was designed to partially automate the wrapping operation, the blanks are fed from a stack in a feed hopper means to a transfer member, and after a core has been placed on top of blank, heat is applied to soften the blank prior to folding. In such a machine complete and thorough heating of the blank under the core may not be satisfactorily accomplished so that fractureless folds are not always accomplished.

In the manufacture of resistors of the above-described type, after an initial wrap is applied to the bare flat metal core the resistor wire is wound around the initial wrap and the core is then wrapped with either a final wrapping blank or is wrapped with a secondary blank in preparation for the application of a second winding which may be followed by one or more additional wrappings and windings before the final wrapping blank is applied. Each wrapping applied after the first must be applied, therefore, to a thicker core than the previous wrapping because of the buildup of windings and wrappings.

In known machines having forming elements which engage the blank and fold it over the core, it has been necessary to make adjustments when changing from an initial wrapping operation to a subsequent wrapping on the same core to compensate for the change in size. Since it is often necessary to run through small batches of resistors having different values or to interrupt a long run of resistors having one value to supply a few resistors

of a different rating which are urgently needed, excessive adjustments each time it is necessary to change from an initial wrapping to a subsequent wrapping, or vice versa, are time consuming and are very undesirable.

It is an object of the present invention to provide a resistor wrapping machine, which will produce a high quality component and yet may operate substantially unattended. It is a further object to provide a machine which may fold onto the resistor core any one of a series of subsequent wrappings for the core without time consuming adjustments of the machine being necessary when changing from one wrapping to another.

According to the present invention, there is provided an indexing turret having thereon a plurality of component holding fixtures each arranged to hold one of the components by its terminals with the plate portion of the component projecting radially outward from the turret. A plurality of work stations are provided around the turret and a component feed means is arranged to load one component at a time from exteriorly of the turret into one each of the holding fixtures indexed to the component feed means at one work station. At another work station, a wrapping means adjacent the turret is arranged to receive the plate portion of the component held by each holding fixture indexed thereto. A wrapping blank feed means is provided for supplying one wrapping blank at a time to said wrapping station, and the wrapping means has actuated folding members for enclosing the plate portion of each component with one of the wrapping blanks.

Thus, each wrapping blank may be individually heated en route to the wrapping means, and this is preferably done by sliding the wrapping blanks, one after the other, along a feed path, and providing a heating means therealong.

In a specific embodiment of the invention, the wrapping means includes a table member having one side adjacent the turret and a blank supporting upper surface. The table member defines a plate portion receiving cavity extending down from its upper surface and having one end open at the side adjacent the turret. A platform member is contained in the cavity for vertical reciprocation and is biased to a raised position with a flat top surface thereof flush with the upper surface of the table member for supporting, in conjunction with the table member, one of the blanks. A plunger means is provided above the cavity for pushing flatwise downward into the cavity the plate portion of each component held in a holding fixture indexed to the wrapping means, and the platform is movable to a lowered position under the plate portion to thereby bend one of the blanks sandwiched between the plate portion and the top of the platform into a U-shaped configuration consisting of a central portion between the plate portion and the top surface and leg portions extending upward beside opposite sides of the cavity. Latch means is provided for locking the platform member in its lowered position, and a distance above the top surface of the platform member in its lowered position, a side former element is movable into the cavity for bending one leg portion of the U-shaped configuration of the blank over to an acute angle over the plate portion. The latch means is then releasable to permit the platform member to travel upwards towards its raised position so that the bent over leg portion of the blank is bent sharply over and onto the plate portion by being forced against the former element. Because the platform member with the plate portion of the core and the partially folded blank therebetween is pushed to a lowered position a distance below the former element, it makes no difference whether there is one or more wraps already on the core. It is the upward travel of the platform that brings the blank being applied into

engagement with former element and this folds the leg portion of the blank over against the core. Moreover, once the upward movement of the platform member stops due to engagement with the former element the upper surface of the core is then automatically properly located for a folding action by the second former element.

FIGURES 25 to 29 are views similar to FIGURE 24, but with parts removed for the sake of clarity, and showing locations of certain elements of the wrapping mechanism during different stages of the wrapping process of a core.

Referring first to FIGURES 2 to 8, and particularly FIGURE 2, the resistor wrapping and winding process is carried out on a core 40 shown in FIGURE 2. The core 40 includes a flat sheet metal body portion 41 having two longitudinal slots 42 and 43 extending in from one end to provide two outside tongues 44 and 45 and a central tongue 46. The tongues 44 and 45 and 46 are embedded in a transversely extending dielectric head 47. Formed integrally with central tongue 46 is a central terminal 49 projecting from the opposite side of dielectric head 47 in the same plane as body portion 41. Formed integrally with outside tongues 44 and 45 are terminals 50 and 51 respectively which project from the opposite side of said head as body portion 40 and are also in the same plane as body portion 40. The terminals 50 and 51 are joined by a cross bar 53 so that the terminals 50 and 51 at the end of the terminals opposite the dielectric head 47 and the cross bar form a U-shaped terminal configuration in the same plane as the body 40 but on the opposite side of the dielectric head 47. The cross bar 53 extends slightly past the terminals 50 and 51 to provide a pair of lateral lugs 54 and 55 extending from the outside of the terminals 50 and 51. As will become apparent below the cross bar 53 and lateral lugs 54 and 55 are used for holding and supporting the resistor during the wrapping operations, and the cross bar and lugs are removed on completion of the manufacture of the resistor so that the outer end of the terminals are free.

In FIGURE 1 of the drawings, the reference character 60 generally denotes the automatic resistor wrapping machine of the present invention. Along one side of the machine 60 there is situated a core storage rack 61 which is adapted to hold a plurality of cores 40, such as the one shown in FIGURE 2, and feeding means 62 is provided to deliver the cores one at a time to a notching machine 63. In the notching machine 63, the core is notched as at 64 in FIGURE 3 to sever either one or both of tongues 44 and 45 to isolate one or both of the outer 50 and 51 from body portion 41 of the core. In the example shown in FIGURE 3, terminal 51 is isolated from body portion 41 by notch 64 and this terminal becomes isolated from terminal 50 also, of course, when cross bar 53 is cut from the terminals in a later operation. After the core has been notched it is pushed into a holding fixture 65 on a transfer turret 66.

The turret 66 has a plurality of identical holding fixtures 65 equally spaced about the periphery thereof, and the turret is arranged to index each holding fixture around to the various stations outside the periphery of the turret, each indexing being equal, of course, to the angular spacing of the holding fixture. Thus, after each indexing of turret 66, an empty holding fixture is situated at a loading station 67 adjacent to the notching machine 63 for reception of a notched core 40a such as the one shown in FIGURE 4. Each holding fixture 65 holds the core 40a by the cross bar 53 with body portion 41 of the core projecting radially outward from the periphery of the turret 66.

The turret 66 shown in FIGURE 1 has six holding fixtures 65, by way of example, and no work is done on the core after the first indexing from the loading station 67 in the direction of arrow 79. However, at the next indexing the core enters a preheat station 68 where the body portion 41 has heat applied to it prior to entering the wrapping station 70 during the next indexing so that the metal body portion does not have a cooling effect on the wrapping.

As each core is being forwarded to wrapping station

70 in the manner discussed above, a wrapping blank 71, which is shown in FIGURE 7, is simultaneously prepared and forwarded to the wrapping station 70. The wrapping blank 71, which is formed of insulating material such as phenolized asbestos, is preferably prepared from a continuous strip 69 of material in a supply roll 72. The strip is fed to a blanking press 73 by a conveyor 74 which carries the strip under a heating device 75. At the blanking press 73 the blanks 71 are stamped from the strip, each blank 71 being then transferred one at a time along a conveyor 76 which extends under the blanking press 73 at one end and feeds each blank 71 to an oven conveyor or feeder 77 at the other end. The oven feeder 77 passes each blank 71 through an oven 78 and then delivers the heated and thus sticky and softened blank 71 to the wrapping station.

At the wrapping station 70, each notched core 40a is wrapped with one of the blanks 71, the blank 71 being folded substantially along longitudinal lines 80, 80 and as the blank 71 is shorter than body portion 41 and is provided with a pair of rectangular notches at one end, the end of the body portion 41 remote from dielectric head 47 and the tongues 44 and 45 are left exposed as is shown in FIGURE 4. After the wrapping operation at the wrapping station 70 each wrapped core 40b is indexed to a sealing station 81 at which the wrapped core 40b is simply pressed to insure that the overlapping portions of the wrapping are sealed to each other and that the wrapping is stuck to the body portion 41 of the core 40b. Next the core with the wrapping thereon is indexed to a discharge station 82 where the wrapped core 40b is ejected into a discharge chute 83. From discharge chute 83 the wrapped core 40b slides onto a conveyor 84 which carries the wrapped core 40b from machine 60 to another machine or a storage container, such as a tote box, for example.

After the wrapped cores 40b are discharged one at a time from the machine 60 of the present invention, they are delivered to a working machine (not shown) where resistance wires 86 are wound about the wrapping and have their ends welded, for example, to the exposed outer end of body portion 41 and exposed tongue 45 which is integral with terminal 51 and isolated from body portion 41, whereby wound core 40c shown in FIGURE 5 is produced. The wound cores 40c are then placed in rack 61 to be again fed through the machine 60. The second time through machine 60, the cores have another wrapping blank 71 applied thereto in preparation for yet another winding of resistance wire or the cores have a final wrapping blank 87, which is shown in FIGURE 8, applied thereto. If a second blank 71 is being applied, the operation is the same as that described above, except that notching machine 63 is not operated since the necessary notching is completed the first time through, nor is the preheat station 68 operated as the second wrapping blank 71 is not exposed to the bare metal body portion 41. Also, if the second wrap is the operation of applying wrapping blank 87, the notching machine 63 and preheat station 68 are left inoperative, and it is necessary, of course, to change the punch and die of blanking machine 73 so that a blank of the shape shown in FIGURE 8 is punched out and forwarded by conveyor 76 and feeder 77 to wrapping station 70.

As shown in FIGURES 6 and 8, the wrapping blank 87 is nearly as long as body portion 41 and has no notches so that it covers the body portion and the other wrappings and windings thereon. Moreover, the blank 87 has an end flap 88, which is folded over the core under the main portion of the blank so as to completely close in the resistor below the dielectric head 47 when the final wrap is applied. Although the wrapping blank 87 is of a different configuration than the wrapping blank 71 and wound core 40c is bulkier than the notched core 40a, no changes to the mechanism at the wrapping station 70 are necessary for reasons which will become apparent

from the more detailed description of the wrapping station given below.

As is indicated above, the storage rack 61 is provided at one side of machine 60, and reference is now made to FIGURES 9 and 10 which show the rack 61 together with a dispensing means 90 in more detail. The rack 61 includes a pair of horizontal rails 91, 91 between which cores 40 or wound cores 40c are held. The rails 91, 91 are spaced a distance slightly greater than the total length of cross bar 53 including laterally projecting lugs 54 and 55, but each is provided with an inturned bottom flange 92 extending substantially the length of the rail. The opposed flanges 92, 92 on the two rails project inwardly only a distance to carry lugs 54, 55 and are spaced a distance greater than terminals 50 and 51 so that the cores may be freely suspended between the rails by lugs 54 and 55 resting on the flanges 91, 91. The dielectric heads 47 and main body portion 41 hang well below the rails 91, 91 as shown in FIGURE 10.

The pairs of rails 91, 91 which are connected at their upper edges by one or more cross-members 94, are carried well above the level of turret 66, the rails being supported at one end by support member 93 which is secured to one of the rails by screws 95. At the other end, namely the dispensing end of the rails, the rails 91, 91 are supported on a table 96, which also carries dispensing means 90, the rails being connected by angles 98, 98 to a vertical plate 97 which extends transversely relative to the rails and is secured to the table 96.

The rack 61 and dispensing means 90 are provided with a biasing means arranged to engage the last core 40 in the rack and to force all of the cores together and towards the dispensing end. The biasing means 100 includes an additional rail 101 which extends along beside the outside of one of the rails 91, 91 the rail 101 being connected at opposite ends to, but spaced from the adjacent rail 91 by brackets 102 and 103. A carriage 104 is slidably mounted on rail 101, the carriage having a rail receiving channel 105 extending therethrough, whereby the carriage 104 can glide substantially from one end to the other of said rails 91, 91. A flexible chain or cable 106 is connected at one end to a small bracket 107 fixed to the carriage. The cable passes around a first pulley 110 mounted on a vertical spindle 111 secured to table 96 by a bracket 112, the cable thus changing direction passes over a second pulley 113 mounted on a horizontal spindle 114 carried by bracket 112. The depending end of the cable 106 hanging from pulley 113 carries a weight 115 suspended in vertical tubular protector member 116. Thus due to the hanging weight 115 the carriage is always biased to the dispensing end of the rails.

To a downwardly extending flange 117 formed on carriage 104, and arm 120 is slidably connected by screw member 121, 121 received in slots in arm 120 and threaded into flange 117. The arm 120, when in its core engaging position, has an inner end extending under rails 91, 91 and is provided at its inner end under the rails with a projection 122 facing the dispensing end of the rails. The projection 122 is arranged to engage the dielectric head 47 of the last core 40 on the rack, since the dielectric heads 47 are the thickest portion of the cores, and the biasing force applied by weight 115 pushes the dielectric heads of all of the cores on the rack into tight engagement as the biasing force is transferred through the heads of the cores to push the core at the extreme dispensing end of the rails into engagement with a stop member 123. The arm 120 has a handle portion 124 formed on its end opposite projection 122, and the handle portion 124 may be readily grasped to slide the carriage away from the dispensing end against the biasing of weight and to also pull the inner end for sliding the arm out from under the rails.

As will be described in more detail below, the dispensing means 90 is arranged to pick one core at a time from the dispensing end of the rails provided that the

cores are biased towards the dispensing means, each core then being dropped into chute 125 at time intervals equal to the interval between each indexing of turret 66. It should be pointed out before leaving the description of rack 61, however, that the operation of machine 60 need not be interrupted to load rack 61. While one batch of the cores are being forced to the dispensing means 90, a fresh batch can be added behind biasing means 100 without disturbing the operation of the dispensing means. The cores of the new batch may be inserted between the rails 91, 91 from the outer end by pushing the cores out of a carrying rack and directly onto flanges 92, 92 or even by placing them in the rack from below or above the rails by slightly turning the cores from the transverse position until the lugs 54 and 55 are just above flanges 92, 92. Once the new batch is suspended behind biasing means, the inner end of the arm may be pulled out, and the carriage can then be pulled back to the point where the arm can be moved in behind the new batch. As the handle portion 124 is released the new batch is forced into the old by the biasing effect of weight 115 on carriage 104. As carriage 104 is being relocated pressure is maintained on the cores of the old batch by one hand of the operator. Moreover, as it is possible to insert the cores from above or below the rails, it is possible to insert near the dispensing end a few cores of a different value. In the dispensing means 90 the stop member 123, which may be urgently needed includes a vertical portion 126 formed integrally with a horizontal portion 127 extending through slot 129 in plate 97 and having a core engaging face 128 at its free end, is mounted for reciprocation in a channel formed by a pair of spaced flanges 130, 130 extending up from table 96. The stop member 123 is aligned with rack 61, and face 128 is at a level to engage the dielectric head 47 of each core as each core is pushed to the dispensing means 90.

Also slidably mounted in the channel formed by flanges 130, 130 is a block 131, which is attached at its end opposite to the stop member 123 to a piston rod 132 of a pneumatic cylinder and piston type motor 133 secured to table 96 by a bracket 135. The piston rod is normally in the extended position shown in FIGURE 9, but as pressurized air is admitted through conduit 134, the piston rod is retracted. The admission of air through conduit 134 is controlled by a control system (not shown) so that the dispensing means 90 is activated once for each indexing of turret 66.

The vertical portion 126 has a bore 136 therethrough, which reciprocably receives the shank of a bolt 137 threaded into block 131. Surrounding the shank of bolt 137 is a coil spring 138 which is between vertical portion 126 of the stop member and the block 131. The spring 138 normally urges the stop member 123 into engagement with the next core in the rack to be dropped, and the bolt 137 is sufficiently long that the head 140 of bolt 137 does not engage vertical portion 126.

The block 131 has attached to one side thereof by a screw 141 a small angle member 142 which provides a lateral flange 143. The flange extends between an adjustable stop 139, 139a, which limits the stroke of the piston rod 132 to thereby accurately locate block 131 when the piston rod is in its normal extended position and when the piston rod has been retracted by admission of air through conduit 134.

Extending out over the shank of bolt 137, the block has a horizontal flange 144 carrying on its upper surface a vertically extending line 145. A pair of bell cranks 146, 146 is mounted to pivot on vertical posts 147, 147 of table 96 on opposite sides of the channel in which block 131 is mounted. Each bell crank at one end over the flange 144 has a slot 150 which receives pin 145 so that as block 131 is retracted by motor 133 the bell cranks 146, 146 pivot in the direction of arrows 151, 151. Each bell crank 146, 146 has a lower offset portion 152 extending through a slot 153 in plate 97, and the outer ends of the

portions 152, 152 are open ended to provide slots 154, 154. Mounted on the outside of plate 97 on each side of rails 91, 91 is a pair of guides 155, 155. Each one of the pair of guides 155, 155 defines therebetween a channel in which is slidably mounted a core parting-off member 156. As is best shown in FIGURE 10 each parting-off member 156 is held against plate 97 by flanges 157, 157 of guides 155, 155 overlapping lateral flanges 158, 158 on parting-off member 156. The parting-off members 156, 156 are thus slideable towards each other from opposite sides of the dispensing end of rack 61, and each has a pin 160 received in slot 154 of one of the bell cranks 146, 146, so that as motor 133 is activated to retract block 131 and bell cranks 146, 146 are pivoted in the direction of arrows 151, 151, parting-off members 156, 156 are forced towards rack 61 to a core engaging position. Each parting-off member has a wedge shaped nose arranged to move between the core abutting stop member 123 and the one next in line as the parting-off members move in.

As is described above the cores are pushed one after the other against face 128 of stop member 123, and stop member 123 is prevented from sliding away from the cores by coil spring 138. Thus the cores are prevented from sliding off the ends of flanges 92, 92 which terminate a short distance back from plate 97 as best shown in FIGURE 9. When dispensing means 90 is activated, i.e., air is admitted through conduit 134 to cause retraction of block 131 so that flange 143 on block 131 is moved from stop 139 back towards stop 139a, stop member 123 moves back from rack 61 under the force of biasing means 100 transferred through the cores since the compressive force on coil spring 138 is reduced on retraction of block 131. All of the cores are thus advanced towards the dispensing end of the rail and the lugs 54, 55 of the end core abutting face 128 actually clear the end flanges 92, 92. However, the end core does not fall as soon as it leaves flanges 92, 92, since it is still squeezed between the next core and face 128 due to the forces applied in both directions by biasing means 100 and coil spring 138.

As motor completes its retraction stroke, i.e., as flange 143 approaches stop 139a, the shank of bolt 137 has completely moved through bore 136 and head 140 of the bolt engages vertical portion 126 of the stop member 123 and pulls face 128 away from the unsuspended core. Also by this stage of the retraction wedge-shaped noses 161, 161 of parting-off members 156, 156 have been forced by the pivoting of bell cranks 146, 146 in the direction of arrows 151, 151 so that the force of biasing means 100 transferred to the next core between the rails 91, 91 is taken up by parting-off members 156, 156 and the next core no longer engages the unsuspended core. Therefore, the unsuspended core is permitted to drop into chute 125 in which the core slides to a horizontal position. Conduit 134 at this point is exhausted and piston rod 132 is forced to return to its extended position by spring means (not shown) or air pressure applied to the outer end of the motor. As the piston rod returns the block 131 is forced back to its initial position and this motion, through bell crank 146, 146, withdraws parting-off members 156, 156 to permit the core, which until now had been next in line, to engage face 128 as stop member 123 is forced to its initial position by coil spring 128. Then after an interval equal to the time between each successive indexing of turret 66 the core which has taken the end position by the above-described dispensing operation, is dispensed from rack 61 into chute 125 in exactly the same manner.

Chute 125 has a delivery end (FIGURES 11 and 12) below dispensing means 90 and over a top flight 166 of an endless belt conveyor 165 which is part of feeding means 62. The upper flight 166 extends between the chute 125 and a stationary bar 167 having a locating face 168. The endless belt conveyor 165 passes around sheaves 170, 170 and around a drive sheave 171 of a motor 172 mounted below the upper flight. The core 40 or 40c dropped by dispensing means 90 slides down chute 125

and onto upper flight 166 in a horizontal position and at a velocity sufficient to carry the outer end of body portion 40 towards locating face 168. The motor 172 is in continuous operation so that the upper flight 166 continuously travels toward stationary bar 167 as is shown by arrows 164 in FIGURES 11 and 12, and thus, through frictional engagement between the upper flight 166 and the core lying thereon, the core is continuously held against locating face 168 as is shown in phantom in FIGURE 12.

The feeding means 62 has a transfer shelf 173 (FIGURE 11) extending between endless belt conveyor 165 and die member 174 of notching machine 63, the tops of the upper flight 166, shelf 173 and die member 174 all being on the same level with stationary bar 167 extending across the endless belt conveyor and shelf 173 to the die member of the notching machine 63. Suspended by a bracket 176 above endless belt conveyor 165 and on the opposite side as shelf 173 is a pneumatic piston and cylinder type motor 176. Motor 176 has a piston rod 177 which is perpendicular to upper flight 166 and is extended out over upper flight 166, shelf 173 and die member 174 when air is admitted by a control valve (not shown) into the outer end of motor 176 by conduit 178 (FIGURE 12). When conduit 178 is exhausted and air is admitted by the control valve through conduit 179, the piston rod 177 is retracted, to an inoperative position in which a cross bar 182 secured to the outer end of the piston rod is retracted from the upper flight 166 of the endless belt conveyor. Cross bar 182, which reciprocates in a horizontal plane spaced above upper flight 166 and shelf 173 has pivotally connected thereto by pins 180, 180, a pair of spaced dogs 181, 181. The dogs 181, 181, which hang down to the top of the upper flight 166 are arranged to engage the body portion 41 of the core in engagement with locating face 168.

The dogs 181, 181 are sufficiently spaced that they engage the edge of the body portion 41 at substantially opposite ends thereof so that the resistor is pushed squarely, when piston rod 177 is extended, off the upper flight 166 and along shelf 173 with the outer end edge of the core in sliding engagement with locating face 168. Each core is pushed sideways in this manner, as is shown in FIGURE 11, until it is located in notching machine 63 with tongues 44, 45 of the core located over slotted openings 183, 183 of die member 174. At this point the piston rod retracts back to the outside of the upper flight 166 and there awaits the next core to be dropped by dispensing means 40.

The notching machine 63 consists of a punch press 50 having a head 184 (FIGURE 12) mounted for up and down reciprocation on guide pins 185, 185 and being provided with a motor (not shown) for driving head 184 downwardly. Under head 184 two punch members 186, 186 are aligned with and shaped to enter slots 183, 183. Only one of the punch members 186 is set in an operative position, of course, if only one of tongues 44, 45 is to be notched as shown in FIGURE 3 at 64.

Running normal to the direction of travel of cores into notching machine 63 and extending between slotted openings 183, 183 is an open channel 187 of rectangular cross-section. The channel extends to the side of the die member 174 adjacent turret 66 shown in phantom in FIGURE 11. A piston and cylinder type motor 169 is mounted by a bracket 169b on the side of die member 174 opposite to turret 66 and has a piston rod 169a aligned with and extending into channel 187. On the outer end of piston rod 169a is a pushing block 188 (FIGURE 11) which is reciprocably received in channel 187 but has a significant portion projecting above the top surface of die member 174.

As motor 169 is energized by controlled admittance of pressurized air to its outer end, piston rod 169a moves block 188 along in channel 187 towards turret 66, and block 188 engages the outer edge of body portion 41 of 75

the core which has been notched, or simply left by feeding means 63 in the case of a core already wrapped, and pushes the core into an empty holding fixture 65 indexed to the loading station. The core thus travels with cross bar 53 of the core at the advance edge into the holding fixture, the direct transit of the core being guided by two guide blocks 189, 189a arranged on opposite sides of channel 187.

As was explained above, the operation of dispensing means 90 is timed with the indexing of turret 66 so that one core is dropped for each indexing. Similarly, the operation of motors 176 and 169 and the motor operating head 184 of the notching machine 63 is tied in with the turret indexing to deliver the dropped core to the turret at the appropriate time. Moreover, well known control means, such as properly located microswitches, are provided so that the operations of the dispensing means 90, feeding means 69, notching machine 63 and motor 169 are synchronized, whereby each core 40 is dropped, carried into engagement with locating surface 168, pushed sideways into notching machine 63, notched and then pushed cross bar first into a waiting holding fixture 65.

Returning now to FIGURE 1, the conveyor 74 is preferably an endless rubber belt driven by a continuously running motor (not shown) through a clutch-brake combination 190 of a well-known type. A continuous strip 69 of phenolized asbestos having an adhesive coated surface is drawn from roll 72 to blanking press 73 by frictional engagement of the strip with the upper flight of conveyor 74, and a roll 191, which rides on top of the strip 69, may be provided to ensure firm engagement between the strip and belt. The heating device 75 preferably consists of one or more infrared heat lamps mounted over the conveyor 74 in a container 192 for directing the heat rays down onto the strip as it first comes onto the conveyor. The heat is applied to the strip at this stage so as to soften it and remove any residual curved set caused by the strip being contained in a roll. The container 192 preferably has closable shutters (not shown) between the lamps and conveyors with means for closing the shutters when the conveyor is stopped for an extended time so as to prevent heat damage to the strip and conveyor.

The strip 69 is carried by the conveyor 74 straight to blanking press 73 and the strip is fed between the die plates 193, 193 and punch 194 in its raised position as shown in FIGURE 13. The strip 69 is preferably equal in width to the width of either blank 71 or blank 87 so that only the ends of each blank are trimmed to square one end and to form the notched end for blank 71 or the flap 88 of blank 87, the punch and die plate combination of blanking press 73 being shaped to carry out this trimming each time punch 194 descends under the action of a pneumatic press (not shown). On the side of the blanking press 73 opposite to conveyor 74 the die plate has an angled surface 195 which is directly under a bore 196 in support member 197 carrying punch 194. Above the bore 196 is a source of light (not shown) which shines down through bore 196 striking the surface 195 near cavity 200 in die plate 193. The light is thus deflected as indicated by a line 201 in FIGURE 13 to either of photoelectric cells 202a and 202b, one of which is used with blank 71 and the other of which is used with blank 87. The photoelectric cells are mounted adjacent the blanking press 73 (see FIGURE 1). The feed by conveyor 74 and the blanking operation of blanking press 73 are controlled by a central system so that one wrapping blank is produced for each indexing interval of turret 66, but the amount of feed of the strip 69 is controlled by the photoelectric cells 202a and 202b through clutch-brake combination 190.

When either photoelectric cell 202a and 202b is energized by light deflected from surface 197, a circuit is closed which de-energizes the brake portion of clutch-brake combination 190 so that drive is transmitted from

a continuous running motor (not shown) through clutch-brake combination 190 to drive conveyor 74. As strip 69 is fed through blanking press 73 its advancing edge cuts through the light beam to thereby darken the photo-electric cells 202a or 202b. This causes energization of the brake portion of the clutch-brake combination 190 to interrupt the drive of the conveyor. The feed of the strip thus being terminated with a fresh portion of the strip over cavity 200, punch 194 descends to cut a blank which is pushed down into cavity 200.

Punch 194 has a horizontal air passage 203 which is in communication with an air supply conduit 204 via bores 205 and 206. Extending from the lower face of punch 194 up to passage 203 are two or more bores 207, 207 which reciprocably receive plungers 208, 208 which are normally retracted in bores 207, 207. When pressurized air is admitted to passage 205 via conduit 204 and bores 205 and 206 at the time punch 194 reaches its most lower position in a cutting stroke, plungers 208, 208 are driven downwardly due to differential air pressure to a position in which they project below punch 194. The plungers 208, 208 have a headed portion 210, 210 at their inner ends, as shown in FIGURE 13, so that their outward travel is limited, but when passage 203 is pressurized at the bottom of the punch stroke, the plungers project sufficiently from the lower face of the punch 194 to push the freshly cut blank from the punch 194 and drive it to the very bottom of cavity 200. Each plunger 208 has a protuberance 209 on the inner end thereof to hold the headed portion 210 of head of each plunger out of engagement with the side of the passage 203 to ensure that the pressurized air can enter between the headed portion 210 and the top of the passage and thereby ensure that plungers 208 are not held against the top of passage 203 by the air pressure on the under side of the head portions.

Conveyor 76 has one end 214 centered under the cavity 200 of the blanking press 73, the conveyor 76 including a table-like member 215, having a flat upper surface 216 extending from blanking press 73 to oven feeder 77. Referring to FIGURES 14 and 15, it may be seen that the table-like member 219 has two parallel, longitudinal slots 217, 217 therethrough and extending from under blanking press 73 to oven feeder 77, the slots 217, 217 extending perpendicular to the direction of travel of strip 69 into blanking press 73.

Secured below table-like member 215 on opposite sides of slots 217, 217 and extending parallel to the slots is a pair of rail members 220, 220. Each rail member 220 has an inturned horizontal flange 221 extending the length thereof, the flanges 221, 221 supporting therebetween a carriage 222. The carriage 222 includes a pair of parallel elongated bars 223, 223 connected together with a pair of short, transversely extending bars 224, 224 secured in notches 225 and 226 in the top of bars 223, 223. Each of bars 224, 224 is longer than the spacing between longitudinal bars 223, 223 so that they provide laterally extending lugs 227, 227 which rest on flanges 221, 221 and thereby support the carriage 222 for reciprocation in the longitudinal direction of the carriage.

Also under table-like member 215 and at the end 214 of the conveyor 76, there is mounted a pneumatic piston and cylinder motor 230 for reciprocating the carriage 222. The motor 230 which is aligned with carriage 222 is pivotally connected at its outer end by a pin 232 of downwardly depending lug 231 secured to table-like member 215. A piston rod 233 is pivotally connected at its outer end by a pin 235 to a lug 234 secured to and extending below carriage 222. When pressurized air is admitted to the outer end of motor 230 through air conduit 236, the piston rod 233 is forced to a projected position and thereby slides carriage 222 towards oven feeder 77 on a feed stroke. When conduit 236 is exhausted and pressurized air is admitted to the inner end of motor 230 through a conduit 237, piston rod 233 is retracted to pull

the carriage back to its original position on a return stroke.

At the opposite end of rails 220, 220 as motor 230 an adjustable stop means 240 is provided. Stop means 240 consists of a block 241 secured under table-like member 215 and had a bolt 242 threaded thereinto. Bolt 242 is aligned with one of bars 223 whereby the bar 223 engages bolt 242 as carriage 222 moves out on its feed stroke to thereby establish the travel of the carriage.

Mounted between bars 223, 223 are feed dog assemblies 244. Each assembly 244 includes a tubular member 245 rotatably received on a rod 246 secured between bars 223, 223. To tubular member 245 are fixed two wedge-shaped dogs 247, 247 which are spaced to project into slots 217, 217. Each assembly 244 has a weight 250 secured to tubular member 245 so that apex 251 of each dog 247 is biased to a blank engaging position slightly above upper surface 216. Each dog 247 has a tail portion 252 extending on the opposite side of tubular member 245 as apex 251, and engagement of the tail portion 252 with a stop 253 fixed to one of the bars 223 limits the upward travel of apex 251 under the biasing effect of weight 250.

A pair of dogs 247a, 247a at end 214 of the conveyor 25 are simply secured to bars 223, 223 since they are not required to pivot to a retracted position for reasons which will become apparent later. The space between dogs 247a, 247a and the next pivoted dogs 247, 247 is located immediately beneath cavity 200 of blanking press 73 when 30 the piston rod 233 is retracted, and the space, like the spacing between adjacent dog assemblies 244 is slightly greater than the widths of wrapping blanks 71 and 87 so that a wrapping blank can rest on surface 216 between each pair of dogs. The lateral spacing of the dogs in each 35 pair is slightly less than the length of the blanks so that as carriage 222 goes through the feed stroke, each wrapping blank is engaged along one of its side edges by both dogs in a pair.

A plate member 255 extends over surface 216 a short 40 distance thereabove between blanking press 73 and end 218 of table-like member 215 providing a pickup station for the oven feeder 77. On plate member 255 midway between slots 217, 217 is mounted a longitudinally extending bar 256. Bar 256 is slotted at 257, 257, and 45 pivotally mounted in slots 257, 257 by horizontal pins 260, 260 are blank engaging fingers 261, 261. Each of fingers 261, 261 has a pointed lower end 262 below the pivot pin 260 and a weight 263 on its upper end. Since the distance between the pointed lower end 262 and the 50 pivot pin is greater than the distance between the pivot pin and surface 216, the pointed lower end cannot pass under the pivot pin but is biased into engagement with the surface 216 by weight 263 which is on a portion of the finger 261 which is curved back over pivot pin 260. 55 The pointed lower end 262 of each finger 261 engages surface 216 just forward of one of the pairs of dogs when carriage 222 is in its normal position.

A pair of hold-down bars 265, 265 are secured under 60 plate member 255 and are held above surface 216 a distance slightly greater than the thickness of the wrapping blanks. The hold-down bars 265, 265 are parallel to the slots and are situated just outside the slots. As may be seen in FIGURE 15 the ends of the bars 265, 265 facing the advancing blanks are beveled at 266 to assist in 65 the feed of the blanks under the bars 265, 265. Outside of bars 265, 265 there are provided parallel, guide bars 267, 267 which are adjustably secured to surface 216 by bolts 268. The spacing between bars 267, 267 is adjusted so that their opposed guiding edges 269, 269 are spaced 70 a distance just slightly greater than that of the overall length of the wrapping blanks. The ends of edges 269 approaching the advancing blanks are bevelled at 270 (FIGURE 14) so as to guide each blank evenly between the side guide bars 267, 267.

In operation of conveyor 76, pressurized air is admitted

to motor 230 through conduit 236 in timed relationship with blanking press 73. For example, a microswitch may be located to be tripped as punch 194 completes its down-stroke and drops a wrapping blank 71 in front of dogs 247a, 247a which microswitch energizes an air control valve to place conduit 236 in communication with a source of pressurized air. Carriage 222 is thus driven to engagement with bolt 242 and the dropped blank is pushed by dogs 247a, 247a until it passes between side guide bars 267, 267 and under bar 265 and finger 261. As the blank is pushed under finger 261 the lower end 262 pivots up slightly against the biasing of weight 263 to permit passage. Bolt 242 is set so that it is engaged by the carriage 222 just as the blank carried by dogs 247a, 247a passes the lower end 262 of the first finger. At this stage, a properly located microswitch or similar means (not shown) is tripped by carriage 222 to exhaust conduit 236 and admit air via conduit 237 to the inner end of motor 230 whereby piston rod 233 is retracted and carriage 222 returns. When the carriage returns, the dogs 247, 247 of the assembly next in line to dogs 247a, 247a, engage the blank left by dogs 247a, 247a, but the blank engages finger 261 and is prevented from being dragged back. The apexes 251, 251 of the dogs thus tip down to a retracted position against the biasing of weight 250 because of engagement with the held blank and pass under the blank. As soon as the dogs 247, 247 clear the blank, they pivot back up to their normal position. During the next feed and return stroke of the carriage 222, the blank previously carried by dogs 247a, 247a, is similarly carried past the next finger 261, by dogs 247, 247, and on the next feed it is carried to end 218 of the table-like member 215 and there awaits further transfer by oven feeder 77. With each feed stroke, a freshly cut blank is carried, of course, from under blanking press 73 by dogs 247a, 247a, and one wrapping blank is also left for feeder 77 each cycle of operation of conveyor 76.

The outer end 218 of table-like member 215 in effect serves as part of oven feeder 77 which carries each wrapping blank left on the end 218 step-by-step through oven 78 and into wrapping station 70. The oven 78, the location of which is shown in phantom in FIGURE 16, preferably includes a substantially enclosed area having a longitudinally extending infrared bar mounted over the oven feeder 77, the bar being adjustable in height over the conveyor so that the heat delivered to the wrapping blanks on the feeder may be adjusted to compensate for variations in the characteristics of different batches of wrapping material.

The oven feeder 77 is of a different type than conveyor 76 since the blanks become very sticky and soft in oven 78 and a buildup of sticky deposits on the conveyor within the oven would prevent proper function of dogs, such as dogs 247, 247 of conveyor 76, extending up through slots.

Thus, oven feeder 77 includes a table-like member 215 having a flat upper surface 275 which is coplanar with the surface 216 and extends from conveyor 76 to the wrapping station 70. Formed in surface 275 is a pair of parallel, longitudinal grooves 277, 277 which align with a short pair of subsidiary grooves 277a, 277a in surface 216 of table-like member 215 at end 218 and extending perpendicular to slots 217, 217. The grooves 277, 277 at their ends opposite subsidiary grooves 277a, 277a, terminate at the wrapping station 70. Grooves 277, 277 are spaced a distance less than the width of the wrapping blanks.

Along one side of grooves 277, 277, a shaft 280 is journaled above surface 276 in bearings 281 for both rotation and axial reciprocation. To a central portion of shaft 280, which is within oven 78, holding clamps 282 are secured to shaft 280 for movement therewith and the clamps support a bar 283 extending parallel to shaft 280 between the shaft and grooves 277, 277. A plurality of arms 284 are secured at one end to bar 283 and extend out over grooves 277, 277 at right angles thereto, and

each arm 284 has a pair of downwardly projecting fingers or pegs 285, 285 spaced to rest one each in the grooves 277, 277. The spacing between adjacent arms 284 in the longitudinal direction, and therefore, the spacing between adjacent pairs of pegs 285, 285 is a little greater than the overall length of the wrapping blanks.

At one end shaft 280 extends out over the end 218 of table-like member 215 and at that end of the shaft two auxiliary peg holder members 286 and 287 are provided, each of which has a pair of pegs 285, 285 resting in subsidiary grooves 277a, 277a. The pair of pegs in auxiliary peg holder 287 is spaced from the pair of pegs in auxiliary peg holder 286 and from the pair in adjacent arm 284 a distance equal to the spacing between the pegs of adjacent arms 284. At the opposite end of shaft 280 another auxiliary peg holder 288 similar to auxiliary peg holder 287 is provided, and again the pegs 285, 285 of this auxiliary peg holder are spaced from the pegs of the adjacent arm 284 a distance equal to the longitudinal spacing of each adjacent pair of pegs.

Secured under table-like member 275 directly beneath and parallel to shaft 280 is a pneumatic piston and cylinder type motor 290 having a piston rod 291 which is forced to an extended position, shown in chain dotted lines in FIGURE 17, when pressurized air is admitted to the outer end of the motor through conduit 292 and is forced back to a retracted position by admission of pressurized air through conduit 293. A lug 294, which is formed integrally with a collar 295, projects downward through an elongated slot 296 in table-like member 275 and is secured to the outer end of piston rod 177. Shaft 280 is free to rotate within collar 295, but as collar 295 is shifted axially by motor 290, shaft 280 is also shifted axially as the collar 295 abuts clamp 282 at one end and a collar 296, which is fixed to shaft 290, at the other end.

Also secured below table-like member 275 is another pneumatic piston and cylinder type motor 300 which extends perpendicular to shaft 280. The motor 300 has a piston rod 301 pivotally connected to downwardly depending leg 303 at a bell crank 302. The bell crank 302 is mounted for pivotally moving on shaft 280 and the leg 301 extends through a slot 307 in table-like member 275 so that upper, substantially horizontal leg 304 of the bell crank is raised up when the piston rod 301 is retracted due to the admission of pressurized air through an air conduit 305 at the inner end of the motor 300. On admission of pressurized air to conduit 306 at the outer end of motor 300 the bell crank 302 is rotated in a direction to lower upper leg 304. Shaft 280 is free to reciprocate through bell crank 302 and any axial movement of the bell crank with the shaft is prevented by bearing 281 in one direction and in the other direction by a collar member 307 freely surrounding shaft 280 and secured to surface 276.

The upper leg 304 of the bell crank 302 extends out over the grooves in surface 276 and is notched at its outer end 310 to slidably receive a square bar 311. Bar 311, which is parallel to shaft 280, is fixed at opposite ends to a pair of spaced levers 312, 312 fixed to shaft 280 and also extending out over the grooves. Thus, when piston rod 310 is retracted to raise the upper leg 304 of the bell crank 311 is pushed up which raises levers 312, 312, and this action applies a rotating torque to shaft 280.

Secured to the top of table-like member 215 at end 218 is a stop member 314 which is parallel to grooves 277, 277 and is situated on the opposite side of grooves 277, 277 to the terminating ends of slots 217, 217. The stop member 315 is engaged by each wrapping blank pushed to end 218 by dogs 247, 247. Along opposite sides of grooves 277, 277 entirely along the length of table-like member 275 is a pair of side guides 316, 316 which are sufficiently spaced to receive the width of each wrapping blank therebetween, each of side guides 316, 316 being beveled at 317, 317 to assist entry of each blank from table-like member 215.

In operation, oven feeder 77 is timed with respect to transfer turret 66 to slide a heated wrapping blank into wrapping station 70 just prior to the completion of each turret index. Since all of the pairs of pegs 285, 285, which push the blanks, move in unison, during each feed stroke into the wrapping station by the pegs 285, 285 in auxiliary peg holder 288, the pegs 285, 285 of auxiliary peg holder 286 simultaneously commence the travel of a fresh blank delivered by conveyor 76 along its path through oven 78. Motor 290 is arranged to have a stroke equal to the spacing of each adjacent pair of pegs 285, 285. During each feed stroke, which is brought about by the extension of connecting rod 291 of motor 290, the piston rod 301 of motor 300 is in its extended position. Thus, as shaft 280 is shifted to the left as viewed in FIGURES 16 and 17, by motor 290, each pair of pegs 285 slide in grooves 277 towards wrapping station 70 and thereby push a wrapping blank along a distance equal to the longitudinal spacing of adjacent pegs. Before pressurized air is admitted to conduit 293 to retract piston rod 291 pressurized air is admitted through conduit 305 to retract piston rod 301 of motor 300. This action rocks bell crank 302 up which raises bar 311 and through levers 312, 312, so that shaft 280 is rotated to raise all the pairs of pegs 285, 285 out of grooves 277, 277 and above the blanks resting on surface 275. Then piston rod 291 is retracted to move each pair of pegs 285, 285 back over the wrapping blank just shifted by the pair of pegs 285, 285 before it in the direction of feed. During this retraction the bar 311 slides in notch 310 and the pegs are held up. Upon complete retraction of piston rod 291 each pair of pegs is lowered back to its original position before the feed stroke, by piston rod 301 which is then again extended by the admission of air through conduit 306 to lower bar 311. Thus, pegs 285, 285 are located behind the next wrapping blank to be shifted thereby, except pegs 285, 285 in auxiliary peg holder 286 which do not have a wrapping blank in front of them until one is shifted up against stop member 315 by dogs 247, 247 before the next feed stroke of conveyor 77.

Referring now to FIGURES 19 and 20, it may be seen that the transfer turret 66 includes a circular table forming plate 320 supported on top of a vertical indexing shaft 321 which is driven by a motor and a brake and clutch means (not shown) to index a fraction of one revolution and then stop for a preselected interval of time to permit loading and unloading of the holding fixtures 65 and to simultaneously permit work to be performed by preheat station 68, wrapping station 70 and sealing station 81 on the core 40 carried by the transfer turret 66. Since six holding fixtures 65 are mounted on transfer turret 66 in the example shown, the indexing shaft 321 rotates $\frac{1}{6}$ of a revolution or 60° in the direction of arrow 79 in FIGURES 1, 18, and 21, each index. Thus, the complete wrapping process for each core, i.e., from the time the core is picked up by the transfer turret until it is discharged, involves six indexes. As shown in FIGURE 19, the indexing shaft 321 is mounted in bearings for rotation about a vertical axis one bearing being shown at 322, supported in a framework 323. Circular plate 320 is fixed on to an enlarged portion 324 at the top of indexing shaft 321 by bolts 325.

Each one of the holding fixtures 65 has a main body member 326 which is in the main above circular plate 320. The body member 326 has a pair of oppositely extending lateral wing portions 327, 327 each having a vertical bore 330 therethrough (FIGURE 19). For each holding fixture 65, circular plate 320 is provided with a pair of upwardly projecting studs 331, 331 which are slidably received in the bores through wing portions 327, 327. Thus, body member 326 of each holding fixture 65 is mounted on transfer turret 66 for vertical reciprocation on studs 331, 331. The upward travel of the body portion 326 is limited, however, by nuts 332, 332 screwed onto a threaded upper

portion of each stud 331. The wing portions 327, 327 are biased into engagement with the nuts 332, 332 by a pair of coil springs 333, 333 compressed between the body member 326 and plate 320, one each of the coil springs 333, 333 being adjacent studs 331, 331 (see FIGURES 5 and 20).

Between each pair of studs 331, 331 circular plate 320 is notched at 334 at the periphery thereof (FIGURE 19). Body member 326 of each holding fixture has a downwardly extending portion 335 which projects into notch 334. Portion 335 has a channel 336 of substantially rectangular cross-section extending across the outer face thereof, which channel is used to form an interlock with a member of the wrapping station 70 as will be described in more detail below.

The upper surface of body member 326 is provided with a channel 337 (see particularly FIGURES 19 and 20) which extends radially inward, with respect to circular plate 320, from the outer side of the holding fixture 65 a distance substantially equal to the length of terminals 50 and 51 projecting outward from dielectric head 47 of the cores 40, the inner end of the channel 337 terminating with a vertical abutment or shoulder 338 (FIGURES 19 and 20). Channel 337, which has slanted sides, has a bottom surface 339 which is a little wider than the total length of the cross bar 53, including lateral lugs 54 and 55. Formed on the inner side of body member 326 is a tubular member 340 which reciprocably receives a headed pin 341. A bore 342 which is axially aligned with said tubular member 340 extends from the tubular member to shoulder 338. The inner end of tubular member 340 is closed by a plug 343 which is threaded therein and a coil spring 344 is captured between the plug 343 and head 341a of headed pin 341. Thus, the head 341a is normally biased against body member 326 by spring 344. Headed pin 341 extends through bore 342 and has a core engaging outer end 341b which projects outwardly beyond shoulder 338 when head 341a is in engagement with body member 326.

Mounted on top of body member 326 is a clamping jaw 346 which has a pair of downwardly depending lugs 347, 347 having aligned openings receiving a transverse, horizontal pin 348 whereby the clamping jaw is pivotally mounted on top of the body member 326. Clamping jaw 346 has a downwardly depending core holding portion 350 which projects downward in front of shoulder 338, and this holding portion 350, which is not as wide as the space between terminals 50, 51 of the core, has a cross bar engaging surface 351 formed on a notch in the inner side of portion 350, the surface 351 being parallel to and spaced outward from shoulder 338. The spacing between surface 351 and shoulder 338 is great enough to receive cross bar 53. Outer surface 349 is bevelled downwardly and inwardly and converges with surface 351 at the bottom edge of portion 350. Clamping jaw 346 also has an inwardly extending tail 352 which is spaced above an inwardly extending tail 353 of body member 326. Between tails 352 and 353 is a compressed coil spring 354 which through tail 352 biases core holding portion 350 down to engagement with the bottom of channel 339. However, on depression of tail 352 to compress coil spring 354, the clamping jaw 346 is pivoted about pin 351 to raise core holding portion 350 from in front of shoulder 338.

Outward of shoulder 338 a distance slightly less than the length of terminals 50, 51 is an elongated transverse slot 355 which extends down in body member 326 (FIGURES 19 and 22). The slot extends fully across channel 337. Mounted in slot 355 for up and down reciprocation is a terminal engaging bar 356 which has in cross-section a curved convex upper surface 357. Bar 356 extends across the full width of channel 337 and at opposite ends has upright posts 360, 360 which project above wing portions 327, 327 of body portion 326.

Fixed to the underside of bar 356 midway between its end is a downwardly depending peg 361 reciprocably re-

ceived in vertical bore 362 in body member 326 (see FIGURE 19). Also under bar 356 on opposite sides of peg 361 are two coil springs 363, 363 (see FIGURE 20) in engagement with the underside of bar 356 and compressed between body 326 and bar 356. Springs 363, 363 bias bar 356 upwardly to a position in which its upper convex surface is well above the bottom 339 of channel 337 as shown in FIGURE 19. However, the upward movement of bar 356 is limited by a head 364 of peg 361 engaging a shoulder 365 provided by counter bore 366 in the bottom of body member 326 (FIGURE 19). Bore 366 is coaxial with bore 362.

Between its ends, peg 361 is provided with a notch 367. In communication with vertical bore 362 is a horizontal bore 370 slidably receiving a locking pin 371 having a head 372. Pin 371 has peg engaging end 373 shaped to be received in notch 367 and bore 370 is located so that notch 367 is opposite end 373 when upper surface 357 is even with the bottom 339 of channel 337. End 373 of pin 371 is normally biased away from peg 361, however, by a coil spring 374 encircling peg 361 and being compressed between head 372 and body member 326. The travel of pin 371 away from peg 361 is limited by a screw member 375 in body member 326, extending into bore 370 and having an end received in a notch 376 of pin 371. A cam member 377 is secured to circular plate 320 and extends upwardly in notch 334 to provide a camming surface 378 under head 372, the camming surface being arranged to engage head 372 to force pin 371 towards peg 361 against the biasing effect of coil spring 374 on downward movement of body member 326 from its normal, spring biased upper position.

Referring now to FIGURES 21 and 22, a mechanism 380 is provided adjacent notching machine 63, which mechanism in addition to functioning as a component unloading device also assists motor 169 in the loading of the holding fixture at notching machine 63. Mechanism 380 is on a frame member 381 outside of transfer turret and includes a horizontal bar 382 which projects out over the holding fixture 65 indexed to the loading station at notching press 63. The bar 382 is mounted for up and down reciprocation on a vertical post 383 extending upward from a mounting plate 384 carried on frame member 381. The vertical movement of bar 382 is limited by a vertically adjustable stop member 385 carried by a horizontal portion 386 of a stand 387, fixed to and extending up from mounting plate 384, the stop member 385 being located between and being engageable by a pair of vertically spaced horizontal flanges 388, 388 formed on a plate 390 depending from bar 382 (FIGURE 22). The bar 382 is biased to a raised position in which lower flange 388 engages stop member 385 by a coil spring 391 encircling post 383 and compressed between mounting plate 384 and bar 382. Secured below frame member 381 by bracket 392a is a pneumatic piston and cylinder type motor 392 having a piston rod 393 extending up through an opening 394 and secured to bar 382. When pressurized air is admitted to the upper end of motor 392 via conduit 395, piston rod 393 is retracted to pull bar 382 down against the biasing effect of spring 391 until upper flange 388 engages stop member 385.

Secured to bar 382 and extending out over the fixture 65 which has been indexed to the discharge chute 83 is an arm 396. The outer end of the arm 396 is positioned over the tail 352 of the clamping jaw 346 and has a downwardly depending, adjustable, tail depressing member 397 secured thereto. Depressing member 397 is adjusted to push tail 352 of the holding fixture 65 at the discharge chute 83 down when bar 382 is pulled to its lower position by motor 392 so that core holding portion 350 of clamping jaw 346 is raised.

Secured beneath a portion of bar 382 which is over the holding fixture 65 at notching press 63 is a vertical plate 400 which is aligned over bar 356 of the holding fixture. Plate 400 is recessed in its lower middle portion so as to

5

10

20

30

40

50

55

60

65

70

form two outer downwardly extending projections 401, 401 aligned with posts 360, 360, the projections 401, 401 being arranged to push the posts 360, 360 down as bar 382 is lowered by motor 392 so that bar 356 is pushed down into slot 355 below the bottom 339 of channel 337 of the holding fixture being loaded. In the recessed portion of plate 400 a slanted guide plate 402 is fixed, the guide plate 402 sloping downwardly and inwardly relative to transfer turret 66 and being arranged to be lowered to the channel 337 just outwardly of clamping jaw 346.

In operation, piston rod 393 is retracted after the indexing of transfer turret 66 but before motor 169 (FIGURE 11) is energized to push the notched core towards the empty holding fixture 65 which has just been indexed to its loading position adjacent the notching press 63. On lowering of bar 382 by the retraction of piston rod 393, tail 352 of holding fixture 65 at the discharge chute 83 is depressed by depressing member 397 so that clamping jaw 346 is raised from channel 337 and surface 351 of core holding portion 350 moves upward from the cross bar 53 of the just wrapped core. This permits pin 341 to move outward under the biasing effect of coil spring 344 to eject the core from the holding fixture and into chute 83.

Also during downward movement of bar 382, projections 401, 401 engage posts 360, 360 of the holding fixture adjacent notching press 63 to thereby lower bar 356 below channel 337. Guide plate 402 is also thereby lowered to channel 337 as shown in broken lines in FIGURE 22. Thus as core 40 is moved towards the holding fixture the terminals and cross bar thereof enter channel 337, the bottom 339 of channel 337 being level with die member 174. As bar 356 is in a lowered position, it does not interfere. Guide plate 402 helps guide the cross bar 53 of the advancing core into engagement with outer beveled surface 349 of the clamping jaw 346 and this cams the jaw up against the force of spring 354 so that the cross bar slides past core holding portion 351 of the clamping jaw. The cross bar 53 thus engages core engaging outer end 341b of pin 341 and the force of motor 169 (FIGURE 11) acting through the core compresses spring 344 until the cross bar engages shoulder 338 at which point clamping jaw 346 springs back down to capture the cross bar between shoulder 338 and surface 351. Pin 341 is thus held in a cocked, position in readiness to expel the core when tail 352 is pushed down by depressing member 397 after the wrapping operation. After the core has been clamped in the holding fixture by clamping jaw 346, piston rod 169a of motor 169 is retracted, and bar 382 returns to its raised position to permit bar 356 to gain rise. With bar 356 in its raised position, the core extends outwardly from the periphery of the turret and is held in an inclined position by the bar (see FIGURE 19).

As was previously described, once the core is loaded into the holding fixture 65 it is indexed, 60° at a time, and on the second indexing the body portion 41 of the core which is projecting radially outward from the periphery of the transfer turret enters the preheat station 68 (FIGURES 1 and 18). If the cores are having their second wrap applied, i.e., they are wound cores 40c, preheat station 68 is left inoperative. If the cores have no wrapping, the body portion 41 is preheated by a heating element at this station which may include a pneumatic piston and cylinder type motor which forces the heating element into engagement with the body core portion. Thus heated, or after the core has been passed into preheat station 68 but not heated as in the case of a wound core 40a, the core, still held by the holding fixture, is indexed to wrapping station 70 which includes wrapping mechanism 405 illustrated in FIGURES 23 to 29. The wrapping mechanism 405 includes a table 406 which has an upper surface flush with and abutting table-like member 275 of conveyor 76. Table 406 has a pair of grooves 407, 407 which are coextensive with grooves 277, 277 in table-

75

like member 275 so that each blank may be pushed entirely into wrapping mechanism 405 by the conveyor 76 from the back side of table 406 (FIGURE 18).

The table 406 has an opening forming a cavity 410 therein, the cavity 410 being rectangularly shaped in the horizontal plane and slightly bigger than the body portion 41 of the core. The cavity 410 is open at the side of table 406 adjacent the periphery of the transfer turret 66 and in its long dimension extends into table 406 from this side so that on each indexing of the turret the body 41 of the one of the cores extends up over the cavity.

Table 406 has formed therein one channel 411 of less width than the cavity, this channel extending from the back side of the table to the cavity, and reciprocably mounted in this channel is an end flap former 412 which is of the same depth as the channel 411 so that its upper surface is flush with the top of the table (FIGURES 18 and 23). The former 412 has an inner end surface 413 (FIGURE 24) which is normally flush with the side of the cavity 410 opposite the turret 66. At its outer end former 412 has a downwardly depending lug 414 (FIGURE 23) to which one leg of a bell crank 416 is pivotally connected by a pin 415. Bell crank 416 is pivotally connected to a frame member 417, and a piston rod 420 of a pneumatic piston and cylinder type motor 421 is pivotally connected to the other leg of the bell crank. The motor is pivotally anchored at its outer end. Thus, when pressurized air is admitted through a conduit 422 to the outer end of the motor 421 the bell crank 416 is rocked to push the former 412 in the channel towards the cavity 410 to thereby slide the inner end surface 413 a short distance over the cavity. On admission of air to the inner end through a conduit 422, the piston rod is retracted to pull former 412 back to a position in which its inner end surface 413 is again flush with the edge of the cavity.

On opposite sides of cavity 410 is a pair of transversely disposed side flap formers 424, 425 reciprocably mounted in channels 426, 427 in table 406 (FIGURE 24). These side formers are slideable towards and away from the cavity 410, their travel being limited by pins 430, 430 projecting up from the bottom of the channels 426, 427 and into slots 431, 431 in the bottom of the formers 424, 425 which are in the form of rectangular plates. Like end flap former 412, side flap formers 424, 425 are of the same thickness as the depth of their containing channels 426, 427 so that their upper surfaces are flush with the top of the table 406. Each of the formers 424, 425, has an inner end surface 432, 433 which is flush with the long side edges of the cavity 410 when the pin 430 is in engagement with one end of slot 431 such as is shown in FIGURE 24. Each former 424, 425 is provided at the lower portion of the inner end surface with a nonadhering insert, such as "Teflon," 434, 435 extending across the width of the former.

Side flap formers 424, 425 have downwardly depending lugs 436, 437 at their outer ends, and bell cranks 440, 441 which are pivotally mounted on frame member 417 each have one leg pivotally connected to these lugs, by pins 442, 443, respectively. Below frame member 417, two piston and cylinder type motors 444, 445 which are pivotally connected at their lower ends to stationary posts 446, 447. Piston rods 450, 451 of motors 444, 445 extend through openings in frame member 417 and are pivotally connected to the other leg of the bell cranks, and thus when piston rods 450 and 451 are forced to their extending portions by admission of pressurized air through conduits 452, 453, respectively, formers 424, 425, respectively, are forced towards cavity 410 so that inner end surfaces 432, 433 are pushed out over the cavity. Retractions of formers 424, 425 is brought about by admission of air to the motors 444, 445 through conduits 454, 455. As will be explained in more detail, below, motors 444, 445 are independently controlled.

Mounted above cavity 410 on a stand 456 is a press mechanism 460 which has a plunger 461 of rectangular

shape in horizontal cross-section but smaller than the cavity so that when it is forced down from its normally raised position above the table 406 shown in FIGURE 25 it can enter the cavity 410 as shown in FIGURE 24. The lower face of plunger 461 has a non-adhering core-5 engaging pad 462 secured thereto.

The press mechanism 460 also has a plunger means 463 (FIGURES 18 and 23) which is connected to plunger 461 for up and down movement therewith but extends out over the periphery of the transfer turret 66. The plunger means 463 includes a housing 464 carrying a pair of plungers 465, 465. The plungers 465, 465 are over and aligned with posts 360, 360 of each holding fixture 65 indexed to the wrapping station 70 (FIGURES 19 and 23). The pair of plungers is spring-loaded downward by a coil spring 466 and each plunger projects through an opening 467 in the bottom of housing 464 (FIGURE 23). Thus, as plunger 461 commences to descend, plungers 465, 465 engage posts 360, 360 and there-20 by press bar 356 down to compress spring 363, 363 until the upper surface 357 of this bar is even with the bottom 339 of the channel 337 to permit the core to be horizontal (FIGURE 19).

Mounted in cavity 410 is a rectangular platform 470 (FIGURES 24 to 29) which is free for vertical reciprocation therein. Under cavity 410 a tubular member 471 is carried by frame member 417, the tubular member 471 carrying a coil spring 472 which projects through opening 473 in the frame member and engages the bottom of platform 470. Spring 472 normally biases the platform 470 to a raised position in which the upper surface 474 of the platform, formed mainly by a nonadhering insert 475 in the platform, is flush with the upper surface of the table 406, and also with the upper surfaces of formers 412, 424, 425, as shown in FIGURE 25.

The short side of the platform 470 at the open side of the cavity 406, i.e., the side of the platform adjacent transfer turret 66, has a lateral rib 476 (FIGURE 19) which is positioned when the platform is in its raised position to be received in channel 336 of each holding fixture 65 as it is indexed to wrapping mechanism 405. The rib 476 is of rectangular cross section, as indicated in FIGURE 19, for mating reception in the rectangular channel, so that insofar as vertical movement of the platform is concerned, the holding fixture is interlocked with the platform.

Running horizontally along the opposite long sides of platform 470 a distance down from its upper surface 474 are recesses 477, 477. Below the recesses 477, 477, when the platform is in its raised position shown in FIGURE 25, the table has a pair of laterally extending channels 480, 480 reciprocably containing a pair of latches 481, 481. The latches 481, 481 have inner ends 482, 482 which are normally retracted from the cavity but are 55 smaller than recesses 477, 477 so that they may be received in the recesses when the platform has been depressed to thereby hold the platform in a depressed position shown in FIGURES 24 and 26. In the depressed position, the upper surface 474 of the platform is well 60 below formers 424, 425.

A stationary pneumatic and piston cylinder type motor 483 is mounted below frame member 417 and has a piston rod 484 pivotally connected at its upper end to a pair of levers 485, 485 (FIGURES 23 and 24). Each lever 485 is keyed to one of shafts 486, 486 supported by journals 487 under frame member 417. Also keyed to each shaft 486 is an arm 490 which extends up through an opening in frame member 417 and has an upper end 491 received in an opening 492 at the outer end of one of the latches 481. Thus, as air is admitted through a conduit 493 to the upper end of motor 483 to cause retraction of piston rod 484 shafts 486, 486 are rotated through an arc whereby arms 490, 490 shift latches 481, 481 towards platform 470. Similarly, when air is admitted

through a lower conduit 494 to extend piston rod 484 the latches are withdrawn from the platform.

As was previously described, the wrapping blanks 71, or blanks 87 if the wrap is the last, are fed one at a time, top end first as viewed in FIGURES 7 and 8, into the wrapping mechanism 406 by oven feeder 77, while at the same time each core 40 in its raised position is indexed by the transfer turret 66 to the wrapping mechanism. The wrapping blank 71, which is in a heated condition, due to the fact it has just past through oven 78, lies flatly on table 406 and also overlaps the side formers 424, 425 outside of fold lines 80, 80, the portion of the wrapping blank between lines 80, 80 being the portion resting on the platform 470 in cavity 410. When the final wrap is being made the end flap 88 of wrapping blank 87 overlies the end flap former 412. Before plunger 461 commences its first descent immediately after the indexing, the core is held at its oblique indexing angle above the wrapping blank (FIGURES 19 and 25).

When press mechanism is activated by the central control means (not shown) to commence the downward stroke of plunger 461, the core is lowered from its oblique indexing angle so that its body portion 41 lies flatly on top of the wrapping due to engagement of plungers 465, 465 with posts 360, 360 in the manner previously described. Any additional downward movement of plunger means 463 after the core is lowered but before plunger 461 engages the body of the core is absorbed by coil spring 466 as the plungers 465, 465 come into engagement with the top of the holding fixture. However, with continued downward movement of plunger 461 the core body 41 is engaged and plunger 461 continues to move downward to thereby push platform 470 down in cavity 410 against the biasing effect of spring 472. Since the holding fixture body member 326 is interlocked with platform 470 due to rib 476 being received in channel 336 the entire holding fixture is also pushed downwardly with the platform against the biasing effect of spring 333, 333 under the body member 326. Thus, the core which was first lowered to a horizontal position is lowered in its horizontal position as the holding fixture 65 and platform 470 are pushed down in unison by plunger 461. The wrapping blank 71, which is sandwiched between the core body 41 and the upper surface 474 of the platform is thus bent along lines 80, 80 (FIGURE 7) into a U-shaped configuration (FIGURE 24) as the platform moves below the flush upper surfaces of the table 406 and side formers 424, 425. When final wrapping blank 87 is being applied, the end flap 88 is also bent up at substantially right angles relative to the central portion of the blank. The plunger 461 continues its downward movement until the upper surface 474 of the platform is in a lowered position, a considerable distance below the bottom surfaces of the formers 412, 424, 425. In this position of the platform, the recesses 477, 477 are aligned with latches 481, 481 and before plunger 461 returns to its raised position air is admitted through 493 to the upper end of motor 483 to retract piston rod 484 and thereby move latches 481, 481 into recesses 477, 477 (FIGURE 26). Therefore, when plunger 461 is raised from cavity 410 platform 470 is prevented from returning from its lowered position.

As is described above, bar 356 is pushed into a lowered position of body member 326 to permit the core to assume a horizontal by plungers 465, 465, and the bar is retained by the plungers in this position as platform 470 and holding fixtures 65 are lowered in unison. When bar 356 is in the lowered position notch 367 is aligned with pin 371, and as the holding fixture is lowered head 372 engages camming surface 378 of cam member 377 so that end 373 of pin 371 is pushed against the biasing effect of springs 374 into notch 367 (FIGURE 19). Therefore, as the platform 470 is maintained in a lowered position by latches 481, 481, holding fixture 65 is also held with the platform, and pin 371 is retained in notch 367 by cam mem-

ber 377. As plunger 461, and therefore plungers 465, 465 are raised, bar 356 is prevented from returning to its raised position by pin 371. Thus, the body portion of the core lies flatly in a lowered position in the U-shaped wrapping blank on platform 470.

With plunger 461 again in its raised position, motor 421 is actuated to move end flap former 412 towards cavity so that its inner end surface 413 moves a short distance out over the cavity. If the wrapping blank is the final one (FIGURE 8) end surface 413 engages bent up end flap 88 and bends it from an upright position to an acute angular position over the end of the wound core 40c. The actuation of motor 421 is followed immediately by actuation of motor 444 to push side former 424 towards the cavity 410. As inner end surface 432 moves over the cavity a slight distance one side flap 71' of the blank is bent to an acute angle over the body of the core as illustrated in FIGURE 26.

After formers 412 and 424 have been moved in, pressurized air is admitted to motor 483 through conduit 494 to force piston rod 84 to an extended position. This pulls latches 481, 481 from the platform so that spring 472 is permitted to push platform 470 sharply upwards. As platform 470 moves upwards, side flap 71' and end flap 88, if there is one, are bent sharply over and into engagement with the top side of the core being wrapped, and as the core with these flaps bent over are slammed into the bottoms of the formers 412 and 425 a very tight fold of the wrapper over the core is made between the bottom surfaces of the formers and the upper surface 474 of the platform as is illustrated in FIGURE 27.

Since formers 412 and 424 are held in their inner position of this stage the platform is held by these formers at the semi-raised or intermediate position with the core and wrapping blank squeezed tightly between the upper surface 474 and the bottom of the formers as shown in FIGURE 27. As the holding fixture remains interlocked with the platform it also is permitted, of course, to raise to an intermediate position when latches 481, 481 release the platform. The bar 356 remains in its lower position in the body member 326, however, since the head 372 of pin 371 does not clear cam member 377 when the holding fixture is in its intermediate position so that pin 371 remains locked with peg 361. Accordingly, the bar 356 cannot act on the core and attempt to push it up to its raised indexing position.

At this stage motor 445 is activated to cause side former 425 to move towards the cavity 410 (FIGURE 28). The inner end surface 433 thus moves into the cavity to bend flap 71'' over the core. As the flap 71'' overlaps flap 71' the former, and particularly the insert 435 thereof, rubs very tightly over the flap 71'' so that the flap adheres to the core body, or the wound core 40c if the wrap is the final one, and to the other side of flap 71'. All of the formers 412, 424, 425, are then retracted by their respective motors 421, 444, 445 to then permit the spring 472 to return platform 470 to its raised position. The holding fixture 65 also returns to its raised position, and as head 372 of pin 371 clears cam member 377 the core is then raised by bar 356 to its inclined position. However, before indexing plunger 461 descends again so that the wrapped core is again permitted to lie flatly on platform by the action of plungers 465, 465 on posts 360, 360, and plunger 461 engages the wrapped core and through the core pushes platform 470 to its lowered position (FIGURE 29). This step is performed, however, only to apply pressure to the freshly wrapped core 40a to insure adhesion, the wrapping of which is, of course, still warm. Thus, the platform is not at this time latched down nor do any of the formers act. Therefore, the platform and core follow the plunger 461 back up and the now wrapped core raises to its indexing position.

The wrapped core is then indexed to the sealing station 81 and the core carried by the subsequent holding fixture 65 then enters the wrapping station 70 to be wrapped

in exactly the same manner as described above. Sealing station 81 only consists of a press which again applies pressure to the wrapped core to insure good adhesion. On the next index the wrapped core enters discharge station 82, where it is released from the holding fixture due to the depression of tail 352 of the clamping jaw 346 on activation of the loading and unloading plunger mechanism 380.

As was described above in connection with core storage rack 61 it is possible to easily make on the run changes from one batch of resistors to another. Moreover, it is possible to change quickly from a first or intermediate wrap using wrapping blanks 71 to a final wrap using wrapping blanks 87. To change it is only necessary to replace the punch and die in blanking press so that the proper wrapping blank, i.e., either wrapping blank 71 in the case of a first or intermediate wrap or blank 87 in the case of a final wrap, is produced and fed to the wrapping station. Preheat station 68 may be left immobile if the wrap is an intermediate or final as this station is provided to preheat the bare metal body 41 of the core so it will not rob the heat from wrapping blank 71 with which it comes into contact after the next indexing. No alteration is necessary, however, in the wrapping mechanism 405 since the fact the core body 41 is bare or is thicker because one or more wrappings and windings already thereon does not affect the operation. The thickness of the core body and any wrappings and windings does not affect the operation since the platform 470 is pushed well down into cavity 410 so that the core is below the formers prior to the unlocking of latches 481, 481. Therefore, when the latches are released the core is forced into the formers 412, 424 to fold over the first side flap and the end flap if there is one, and the core is then automatically in the right position for former 425 to move in and rub the second side flap down into position.

Since both the feed of the cores and the wrapping blanks and the discharge of the wrapped cores from the transfer turret are automatic the machine may operate relatively unattended, it being only necessary to periodically load the storage rack 61 and provide a fresh roll 72 of wrapping material.

Another feature of the above-described apparatus is the manner in which the wrapping blanks and cores are fed separately to the wrapping station 70 and are only brought together immediately prior to the actual wrapping process. The phenolized asbestos sheet material is very brittle when cold, and therefore, unless the blanks are very thoroughly heated prior to wrapping a good seal is not obtainable and the wrapping may be damaged by cracking. Thus, since the wrapping blank in the apparatus shown is fed directly from the oven where it has been completely exposed to heat, and the bar core body is preheated to prevent robbing of the wrapping blank of its heat, the produced resistors are of good quality.

It is to be understood, of course, that the foregoing description relates to a preferred embodiment of the invention, and other modifications apparent to those skilled in the art may be made without departing from the spirit and scope of the invention defined in the appended claims.

I claim:

1. An apparatus for wrapping a blank of sheet material about a flat plate portion of a component having terminals extending from one end of the plate portion, said apparatus comprising an indexing turret having fixtures each arranged to hold one of the components by said terminals with the plate portion projecting radially outward from the turret, a plurality of work stations spaced circumferentially around said turret, a component feed means for loading one component at a time from exteriorly of said turret into one each of said holding fixtures indexed to one of said stations, a wrapping means at another of said stations arranged adjacent said turret to re-

ceive the plate portion of the component held by each holding fixture indexed thereto, and wrapping blank feed means for supplying one wrapping blank at a time to the wrapping means, said wrapping means having actuated folding members for enclosing said plate portion of each component in one of said wrapping blanks.

2. An apparatus for enclosing a flat plate portion of a component having terminals extending from one end thereof in a wrapping blank of normally brittle sheet material, said apparatus comprising a turret arranged to be intermittently indexed about a vertical axis a fraction of a rotation and provide intervening work periods, a plurality of holding fixtures mounted on said turret about said axis for holding one each of said components by the terminals thereof with the plate portion extending radially outward from the turret, a plurality of work stations spaced circumferentially around said turret, a component feed means for conveying components during each work period from exteriorly of said turret into one each of said holding fixtures indexed to one of said work stations, a wrapping means for receiving each component indexed consecutively from said one station to another station, said wrapping means including forming elements for folding one of the blanks over the plate portion of each component during each work period, a blank feed means for supplying one blank at a time to said wrapping means, said blank feed means including transfer means for moving said blanks one after the other along a path to said wrapping means, and a heating means along said path for heating each blank for softening prior to the entry into said wrapping station.

3. An apparatus as defined in claim 2, wherein said transfer means of said blank feed means includes a first elongated table-like member having a flat, blank supporting, top surface, said top surface having parallel grooves therein extending to said wrapping means, a shaft mounted parallel to said grooves for both longitudinal reciprocation and rotational oscillation, first motor means connected to said shaft for reciprocating said shaft from an initial position towards said wrapping means in a feed stroke and then back to said initial position in a return stroke, a plurality of arms fixed at one end to said shaft and having free ends over said grooves at spacings in the longitudinal direction of said grooves equal to the length of said feed stroke, downwardly depending, blank engaging fingers carried by each arm and extending down into said grooves, and second motor means connected to said shaft for rotating said shaft to raise said arms and thereby lift said fingers above said top surface during the return stroke of said shaft.

4. An apparatus as defined in claim 3, wherein said heating means includes a heating element supported above the top surface of said table-like member.

5. An apparatus as defined in claim 3, wherein said blank feed means further includes a blanking press for cutting one wrapping blank after the other from a continuous strip of said sheet material, a conveyor for feeding the continuous strip from a supply roll to the blanking press, and conveyor means for transferring one blank after the other from said blanking press to said table-like member.

6. An apparatus as defined in claim 5, wherein said conveyor means for transferring said blanks from said blanking press comprises a second elongated table-like member having a flat blank supporting, top surface extending from under a blank outlet of said blanking press to said top surface of said first table-like member, said second table-like member having parallel longitudinal slots extending therealong, a carriage member mounted below said slots for longitudinal reciprocation thereunder, third motor means connected to said carriage for reciprocating said carriage an initial position towards said first table-like member in a feed stroke, and then back to said initial position in a return stroke, a plurality of sets of dog members pivotally mounted on said car-

riage at longitudinal spacings equal to said feed stroke of said carriage, each set of dog members being biased to a blank engaging position projecting upwardly through said slots and above the top surface of said second table-like member and being retractable into said slots due to engagement with blanks on the top surface of said second table-like member during the return stroke of said carriage.

7. An apparatus for wrapping a blank of sheet material about a flat plate portion of components having coplanar terminals extending from one end of the plate portion, said apparatus comprising an indexing turret, a plurality of component holding fixtures mounted at circumferential spacings on said turret for holding one each of the components by said terminals with said plate portion projecting radially outward from said turret, a plurality of work stations spaced circumferentially around said turret, and a wrapping device located at one of said work stations and including a table member having one side adjacent said turret and a blank supporting upper surface, said table member defining a plate portion receiving cavity extending down from said upper surface with one end of said cavity being open at said one side of said table member, a platform member contained in said cavity for vertical reciprocation and being biased to a raised position, said platform member having a flat top surface flush with said upper surface of said table member in said raised position for supporting the blank therewith, a plunger means above said cavity and movable into said cavity for pushing the plate portion of one of said components flatwise down into said cavity after indexing of said one component held by one of said holding fixtures to said wrapping device, said platform member being movable to a lowered position by downward movement of said plate portion to thereby bend the blank then sandwiched between said plate portion and said top surface into a U-shaped configuration having a central portion between said plate portion and said top surface and a pair of leg portions extending upwardly beside opposite sides of said cavity, latch means for locking said platform in said lowered position, and a first blank side former element movable partially into said cavity from one side thereof a distance above the top surface of said platform member in said lowered position for bending one leg portion of the U-shaped blank to an acute angle over said plate portion in said cavity, said latch means being releasable from said platform member after movement of said former element into said cavity to permit said platform member to move upwards towards said raised position whereby the bent over leg portion is folded sharply over and into engagement with said plate portion by being forced against said former element.

8. An apparatus as defined in claim 7, and further comprising a second side former element opposite to and coplanar with said first side former element and movable into said cavity towards said first side former element subsequent to the upward movement of said platform member for bending the other of said leg portions over said plate portion and onto the already folded first leg portion.

9. An apparatus as defined in claim 8, wherein said side former elements are contained in aligned channels formed in said upper surface of said table member extending outward from opposite sides of said cavity, said side former elements having upper surfaces flush with said upper surface for supporting said blank with said upper surface and said top surface of said platform member in the raised position.

10. An apparatus as defined in claim 7, and further comprising an end flap former element coplanar with said first side former and movable partially into said cavity from the end of said cavity opposite to said turret prior to the upward movement of said platform member for bending to an acute angle over said plate portion an end flap bent up from the central portion of said U-shaped configuration on inward movement thereof and for folding

70
75

said end flap sharply over on said plate portion on the upward movement of said platform member.

11. An apparatus as defined in claim 7, wherein each holding fixture has a body member, and wherein said platform member and said body member include means for interlocking in the vertical direction upon each indexing of a holding fixture to said wrapping device whereby up and down movement of said platform member is imparted to the holding fixture during wrapping of the plate portion of the component held thereby.

12. An apparatus as defined in claim 11, wherein the interlocking means comprises a lateral rib formed on one of the interlocking members, the other of said interlocking members defining a horizontal channel facing said one of the interlocking members for longitudinal reception of said rib on indexing of the holding fixture to said wrapping device.

13. An apparatus for wrapping a blank of sheet insulating material about a flat plate portion of components having a U-shaped terminal portion defined by a pair of spaced terminals extending coplanar from one end of said plate portion and a crossbar joining the outer ends of said terminals, said apparatus comprising a turret mounted for arcuate indexing about a vertical axis, a plurality of work stations circumferentially spaced around said turret, a wrapping device at one of said work stations and including a table having one side adjacent said turret and a blank supporting top surface, said wrapping device having a downwardly movable, blank folding plunger above said top surface, and a plurality of holding fixtures on said turret circumferentially spaced about said axis, each holding fixture including a body member having an upper surface and defining a shoulder extending upward therefrom perpendicular to a radial line of said turret, a clamping jaw pivotally connected to said body member and having a component retaining portion biased down into engagement with said upper surface radially outward from said shoulder a distance sufficient to receive the crossbar of one of the components with the plate portion thereof extending radially outward from the holding fixture and turret, and a component engaging member biased upward from a retracted position below said upper surface to a raised position above said upper surface radially outward from said component retaining portion for supporting said one component at an oblique indexing angle extending upwardly and outwardly from the crossbar thereof held between said shoulder and said component retaining portion, said component engaging member having a portion engageable and movable by said plunger for lowering said component engaging member to said retracted position to permit said one component to assume a substantially horizontal position over a blank lying on said top surface of said table.

14. An apparatus as defined in claim 13, wherein said table defines a plate portion receiving cavity under said plunger, said cavity extending down from said top surface and having one end open at said one side of the table adjacent said turret, wherein a platform member is contained in said cavity and is compressible to a lowered position in said cavity, and wherein said body member of the holding fixture is mounted on said turret for movement from a normal raised position to a lowered position, whereby said body member is permitted to move to said lowered position and thereby retain said one component horizontal as said plunger pushes the plate portion of said one component flatwise down into said cavity to bend one of said blanks sandwiched between the plate portion and the platform member into a U-shaped configuration having a central portion between the plate portion and the platform member and a pair of leg portions extending upwardly besides opposite sides of said cavity.

15. An apparatus as defined in claim 14, wherein said platform member and said body member are provided with means for interlocking in vertical movement, said means comprising a lateral rib formed on one of the

interlocking members, other of the interlocking members defining a horizontal channel facing said one member for reception of said rib on indexing of the holding fixture to the wrapping device, whereby movement of said platform to the lowered position imparts like movement of the body member to the lowered position.

16. An apparatus as defined in claim 15, wherein first locking means is provided for holding the interlocked platform member and body member in the lowered position, and second interlock means is provided in said body member for holding said component engaging means in said retracted position, said second locking means including a locking pin movable to a locking position by engagement with a cam member secured to said turret on downward movement of said body member.

17. An apparatus as defined in claim 13, wherein said holding fixture includes a crossbar engaging ejection pin received in a bore in said shoulder, said pin being biased to project outward from said shoulder and movable to and held in a retracted cocked position by engagement with the crossbar of one of said components inserted into the hold fixture, and said apparatus further comprises a component unloading device at one of said work stations after said wrapping device in the direction of index of said turret, said unloading device having means engageable with said clamping jaw for raising said component retaining portion and thereby permitting said pin to move outward from said cocked position and eject the component from the holding fixture.

18. An apparatus as defined in claim 17, wherein said component retaining portion has a downwardly and inwardly sloping, outer surface providing a camming face for producing a raising force on said component retaining portion by engagement against said face by the crossbar of one of the components being pushed into the holding fixture, and said apparatus further comprising a loading device at one of said work stations after said unloading device in the direction of index of the turret, said loading device including a ram means for pushing one component at a time crossbar first into each holding fixture indexed to the loading device.

19. An apparatus as defined in claim 18, wherein said unloading device includes motor means for moving the clamping jaw engageable means from an inoperative to an operative position after each indexing of the turret, and wherein said unloading device carries a component guide means movable to an operative position adjacent said loading device on movement of said clamping jaw engageable means to the operative position for directing each component pushed by said ram means into each holding fixture indexed to the loading device.

20. An apparatus for wrapping a blank of sheet material about a flat plate portion of components each having a U-shaped terminal portion coplanar to said plate portion and extending from one end thereof, said U-shaped portion being defined by a pair of spaced parallel terminals and a crossbar extending between outer ends of the terminals, said crossbar projecting past said terminals to form small lateral lugs outside of said terminals, said apparatus comprising an indexing turret having a plurality of component holding fixtures circumferentially spaced on said turret for holding one each of the components by the cross bar thereof with the plate portion projecting radially outward from the turret, a plurality of work stations spaced circumferentially around said turret, a wrapping device at one of said work stations for receiving the

projecting plate portion of the components and having means for feeding one wrapping blank at a time thereto, and a component feed device at another of said work stations and including a rack having a pair of horizontal, component carrying, parallel rails, said rails having opposed inturned flanges for slidably supporting thereon the lateral lugs of the components located crosswise therebetween with the plate portions hanging therebelow, biasing means between said rails for urging a plurality of interengaging side-by-side components on said flanges flatwise towards a delivery end of the rails, a stop member at the delivery end of the rails for engagement with the first of the plurality of components at said delivery end of the rails, said stop member being retractable from said delivery end to permit said first component to be pushed flatwise off said flanges by said biasing means, parting-off members movable between said first component and the next component at the delivery end on retraction of said stop means for retaining said second component on said flanges and freeing said first component to fall from between said stop member and said second component, and delivery means for catching and moving the falling component into one of said holding fixtures.

21. An apparatus as defined in claim 20, wherein said biasing means comprises a carriage mounted for longitudinal sliding on a rail beside and parallel to said pair of rails, weight means connected to said carriage and urging said carriage to slide in the direction of the delivery end, and an arm connected to said carriage and projecting between said rails for engagement with the last component of said plurality of components, said arm being shiftable to a retracted position away from said pair of rails.

22. An apparatus as defined in claim 21, wherein said delivery means comprises a chute having a delivery end for directing said falling component horizontally with said plate portion forward, a belt-type conveyor having a top flight aligned with the delivery end of the chute and running away from delivery end of the chute to a locating face crossing and extending away from said flight, a first ram means for engaging each component delivered by said top flight to said locating face and pushing the delivered component edgewise and parallel to said locating face to a preselected location removed from said top flight, and a second ram means for engaging each component at said preselected location and pushing the component crossbar first from said preselected location into one of said holding fixtures.
